UNITED STATES PATENT OFFICE.

CLARK J. BROWN, OF PETERSBURG, VIRGINIA.

CORNER GUIDING SCREEN-FRAME BRACKET.

1,036,439.

Specification of Letters Patent. Patented Aug. 20, 1912.

Application filed November 29, 1910. Serial No. 594,674.

To all whom it may concern:

Be it known that I, CLARK J. BROWN, a citizen of the United States, and a resident of Petersburg, in the county of Dinwiddie 5 and State of Virginia, have invented certain new and useful Improvements in Corner Guiding Screen-Frame Brackets, of which the following is a specification, reference being had to the accompanying drawings.

10 This invention relates to certain novel improvements in brackets.

The primary object of my invention is to so construct a sheet metal corner guiding bracket as to permit the same being clasped 15 upon the beveled or otherwise shaped ends of two frame battens for the purpose of matching the ends at an angle and slidably holding the bracket to a guiding strip to eliminate the use of saw kerfs at the corners, 20 guide grooves and tongues within the edges of the battens.

A further object is to provide a corner bracket especially adapted to be used in connection with the window screen frames sold 25 in a disjointed or knocked-down condition to be assembled by the purchaser, enabling him to construct a frame which will be exceedingly rigid at the corners.

A still further object is to provide a complete bracket made of a single piece of metal 30 including a triangular main securing part with two triangular auxiliary securing portions held parallel to said main portion with two intervening parts at right angles to said 35 securing portions, each having two apertured securing strips.

With these and other objects in view, the present invention consists in the combination and arrangement of parts, as will be 40 hereinafter more fully described and particularly pointed out in the appended claims, it being understood that changes in the specific structure shown and described may be made within the scope of the claims without departing from the spirit of the invention.

In the drawings forming a part of this specification, and in which like numerals of reference indicate similar parts in the several views:—Figure 1 shows an elevational view of a window frame with parts broken away united by means of a plurality of brackets embodying my invention. Fig. 2 is a section on line 2, 2 of Fig. 1. Fig. 3 is

a section on line 3, 3 of Fig. 1. Fig. 4 is a 55 section on line 4, 4 of Fig. 1. Fig. 5 shows a perspective view of one of the corner brackets.

In the construction of that class of frames which are sold in a disjointed or knocked- 60 down condition and used to give support to wire netting including both the sliding and swinging varieties known as window screens and door screens, it is quite essential that the frame parts, as well as the method of connecting the same be exceedingly simple so 65 that the frame may be assembled by any one capable of using a saw or hammer.

In my present invention I provide a corner bracket so constructed that the frame 70 parts will all be battens square in cross section without any saw kerfs, grooves or tongues. Heretofore, where sheet metal corner brackets have been used, it has been necessary to twice slit each end of each batten 75 to provide a seat for the wings or plates of the bracket. This slitting or kerfing of the battens at their ends not only weakens the strips at the point where the greatest strength is required, but unless the kerfs 80 run exactly parallel one with the other and are correctly spaced, the bracket wings cannot be inserted into the kerfs. To provide these parallel slits and matching the slits of one batten with those in the other is a task 85 requiring skill in the handling of tools. Further, if the slots are not properly spaced in relation to the thickness of the battens, one batten will be out of alignment with the other so that an unsightly and inoperative 90 structure results. So also has it been necessary heretofore to provide a guide batten having a tongue arranged to slide within the groove of the battens held in a vertical position. This requires that each bundle of 95 knocked-down frame parts be carefully selected so that there are two battens having grooves and two battens that are plain. This grooving, as well as the forming of the tongue, as well as the kerfing of the batten 100 ends, requires an operation in no way necessary in the use of my clasping corner guiding bracket. In my present invention the battens are of such a thickness that the brackets can be readily sprung upon the 105 same to be held by means of suitable nails or screws.

In carrying out the aim of my invention

I employ a sheet metal blank which may be round, oval, oblong or square, though the square form is preferred. For the sake of ornamentation the edges of the blank are scalloped as is shown in Figs. 1 and 5.

5 The plate is provided with two sets of obliquely running incisions, the incisions of each set extending parallel, each set of incisions forming a securing strip or tongue marked 2, 2' and shown in Fig. 5. As shown 10 the incisions forming the strips 2 are located in prolongation of the incisions forming the strap or tongue 2', thereby providing the intervening part 3. The blank is then 15 formed to provide the two similar approximately triangular securing plates 4 and 5. These portions are held in parallel spaced relation as shown in Fig. 2 and are apertured as are the strips 2, 2' to receive the 20 securing nails or screws, 6, by means of which the brackets are secured to the frame.

In Fig. 1 I have shown a window frame including the top and bottom stiles 10 and 11, the vertical stiles 13 and 14 and the middle bar 15. As disclosed the top stile 10 is 25 secured to the vertical stiles 13 and 14 by means of a corner bracket having its securing members 4 and 5 held in parallel spaced relation, both members 4 and 5 extending 30 in like directions while their edges overlap the edges of the vertical stiles as clearly disclosed in Fig. 1. This is an important feature as the projecting bracket portions serve 35 as guide flanges so that the frame may be held to two ordinary square wooden guide battens permitting the frame being raised and lowered. Where the corner brackets are used upon swinging or door frames the vertical stiles must be wide enough so that, 40 the vertical edges of the corner brackets will not project beyond the same. Along the lower edge of a window or door frame where the screen is subjected to the greatest strain in that pressure is occasionally brought upon 45 the screen in operating the same, I prefer using a corner bracket comprising two similar members 4' and 5', these members however extending in opposite directions though held in parallel relation as clearly 50 shown in Fig. 5. If desired where this form of bracket is used a triangular securing plate 8 conforming to portion 4' may be secured to the frame as will be understood in referring to Fig. 3. If it is necessary 55 to use a cross bar in order to brace the frame the intervening part 3 can be provided with an opening 7, shown in Fig. 5, into which is stepped the tenon or end of the brace bar. As disclosed each securing portion 4, 60 5, and 4', 5' has a straight base edge α which in both forms extends from a common plane. In one form of bracket the securing portions extend in like direction while in the other form they extend in opposite directions in the manner stated.

Where a middle bar as 15 is used I employ a specially constructed bracket consisting of a single piece of sheet metal including the triangular main portion 20, the two oppositely positioned intervening parts 21 and 21' which are held at right angles to the portion 20. An apertured securing strip 23 and 24 extends from each part 21 and 21', while extending from the parts 21 and 21' are the securing portions 25 and 26 of similar outline, each of an area approximately half that of the main portion 20. These reduced portions 25 and 26 are apertured as are the strips 23 and 24 to receive suitable nails or screws. The portions 25 and 26 are held parallel to the main portion 20 as is disclosed in Fig. 4. The ends of the triangular portions 20, 25 and 26 may be bent at right angles to serve as clenched points if desired, as shown in Fig. 4.

It is of course understood that the intervening portions 3 and 21 must be of a width equal to the thickness of the frame parts to which the brackets are secured. The intervening parts are further of a length less than the bases, α , of the securing portions. The ends of the straps may also be pointed and used as clenched points.

A bracket constructed according to my invention is noticeable because of its extreme simplicity, neatness and strength. The brackets can further be readily attached to the frames and made to serve in connection with both door and window frames, as well as other frames where the members are to be securely united at the joints.

Having thus described my said invention what I claim as new, and desire to secure by United States Letters Patent is:—

1. A complete corner bracket consisting of a single piece of metal including two securing portions held parallel and extending in opposite directions with a flat and apertured intervening connecting part at right angles to said parallel portions, and two integral intervening securing strips extending at an angle to one another from said intervening parts.

2. A window screen frame comprising four members including a top, bottom and two side stiles, of a sheet metal corner bracket clasped upon said frame over the inner edge at each corner, each bracket including an intervening part having two securing ears and two integral approximately triangular shaped parallel held apertured plates, the securing plate portions clasping the side stiles overlapping the outer edge of the same to form two parallel held guide flanges adapted to clasp a suitable guide batten, each of said ears being secured to the inner edges of said frame to unite said frame at the corners, as and in the manner set forth.

3. As a new article of manufacture a sheet

130.

metal one piece corner guiding screen frame bracket, including two approximately triangular plate portions held in parallel spaced relation and connected by an intervening portion ending in securing ears, said parallel portions being arranged to clasp upon a frame in a manner permitting the edges of said bracket upon one side to over-

lap the connected frame portions, as and for the purpose set forth. 10

In testimony whereof I affix my signature, in presence of two witnesses.

CLARK J. BROWN.
